UNITED STATES PATENT OFFICE.

PAUL L. CLARK, OF BROOKLYN, NEW YORK.

APPARATUS FOR THE ELECTRICAL TRANSMISSION OF VISUAL IMAGES.

Application filed March 26, 1923. Serial No. 627,815.

My invention relates to improvements in machines for the transmission and receiving of electrical or magnetic impulses, either by wire or radio, of point by point, line by line, or spot by spot, scenes at one location so that an image of the scenes may be produced upon a screen or photographic plate for observation at a distant point or station; or for the transmission or reception, or both, or periodic or non periodic waves produced by means of light waves or electrically, magnetically or otherwise; and the object of my invention is to provide a simple optical and mechanical arrangement for both or either the receiving and sending apparatus.

I attain these objects by the mechanism illustrated in the accompanying drawings in which—

20 Figure 1 is a horizontal sectional part plan of the transmitting apparatus; Fig. 2 is a horizontal sectional part plan of the receiving apparatus; Fig. 3 is a horizontal sectional part plan of a system similar to that shown in Fig. 1; Fig. 4 is a broken elevation showing a modified mechanism similar to that in Fig. 3; Fig. 5 is a diagrammatic section through the axes of the several component parts shown, showing paths of rays to and from a screen provided with curved specular elements (similar to that described in applicant's Patents 1,122,192, 1,279,262, 1,535,985 and his copending application Ser. No. 18,241); Fig. 6 is a sectional view of a circular disk provided with adjustable reflectors like those shown in Figs. 1, 2 and 3; Fig. 8 is a section of Fig. 6 on A—A; Fig. 7 is an end elevation of a part of a circular disk having oblique reflecting elements, this disk being a modification of the disk shown in Figs. 6 and 8; Fig. 9 is a front elevation of an adjustable aperture plate for use with the mechanisms shown in Figs. 3 and 4; Fig. 10 is a part 40 plan of a modified arrangement like that in Fig. 2; Fig. 11 is a cross-section of a curved reflecting screen claimed in my copending application S. N. 715,350 which may be used with the apparatus shown in Figs. 1, 2, 3, etc.; Fig. 12 is a front elevation of a part 50 of a prismatic ring similar to that shown in applicant's Patent No. 842,860, this ring to be used to take the place of the reflecting rings or disks shown in Figs. 6, 7, 8, and for tracing parallel or substantially parallel, or 55 slightly eccentric rings or bands of light

of equal or variable width or intensity, or both width and intensity on the screen surface; Fig. 13 is a section of Fig. 12 on B—B; Fig. 14 is a plan view showing diagrammatically an arrangement for using a bank of independent cells sensitive to light variations; Fig. 15 is a front elevation of a shutter for use in instruments using four disks; Fig. 16 is a diagrammatic elevation showing the sequence of the reflecting elements on adjacent disks; Fig. 17 is a plan view of a modified system using a shutter and having a bank of light-sensitive cells; and Fig. 18 is a front elevation of Fig. 17.

Similar numerals refer to similar parts throughout the several views.

In Fig. 1, an illuminated spot *p* (being one of many small spots of different shade or color or tone comprising the picture to be transmitted) reflects certain rays of light which enter a lens *a* and are focused upon a spot *p*¹ on a reflecting screen *s*¹ which may be either matt or specular as desired. Certain rays from *p*¹ are reflected in the direction indicated by the arrowed line 9 and fall upon the revolving disk 18 which is provided with oblique reflecting elements 17 which reflect the rays 9, as shown at 10 (the width of this reflected pencil of rays being shown at 11) to pass through the aperture plate 12 and fall upon the cell 13 which may be of selenium or any cell whose electrical conductivity or whose effect upon or cooperation with any electrical circuit or current is affected to vary or produce electrical impulses of an intensity substantially proportional (or varying in predetermined extent) to the intensity through equal periods of exposure to pencils of light of substantially equal size or cross-section falling upon the said cell. And to this end it is desirable, when moving pictures are to be transmitted, that the cell 13 reach its saturation point in the minimum period required for its exposure to one spot of the view to be transmitted, and also that the effect of the brightest spot impulse received upon the cell be deadened or neutralized (so that at the end of any given impulse produced the effect will not continue over into the period to be given to the next exposure) in order to confine the effects within the duration and limits of the brightest and darkest spots, such that for instance, two bright spots in succession will not produce one semi-bright and one over-bright spot, which is the characteris-

tic of selenium cells; i. e., the sensitivity of the cell should be such that there is substantially zero inertia in the system. From the cell 13, wires 14, 15 lead off through suitable electrical connections and auxiliaries (not shown) to either a wire or wireless (broadcasting) electrical transmission system which deliver the impulses produced in the circuit 14, 13, 15 to the circuit 16, 21, 16^a, Fig. 2. The disk 18 is driven by a motor 19, the whole revolving about the axis 20, the operation of the system being that as the disk 18 revolves rapidly, each element 17 reflects over successive vertical or horizontal strips 1, 2, 3, etc., of the screen s¹ a strip of light from the view, the paths of the rays being shown by the arrowed lines. It is also possible to use the transmitting mechanism direct without the interposition of the lens a and screen s¹, by considering the view itself as occupying a space in the angle subtended by the screen, in which case it will be advantageous to provide elements on the disk 18 which are either plane or concaved to a degree to effect a slight concentration and focusing of the rays upon the aperture plate 12, to the end that too great scattering of rays and confusion of points due to overlapping be avoided; in order to secure sharpness of definition. A converging or diverging lens (not shown) may be placed either in front or rear of the aperture plate 12 to secure proper disposition of the rays over the cell 13, when desired.

In Fig. 2, rays from a light source L are received by the lens b and concentrated upon a reflecting diaphragm 22 whose configuration depends upon the strength or frequency of the impulses received in the circuit 16, 21, 16^a, so that a strong impulse renders the diaphragm 22 of such concavity that it acts to focus substantially all the rays received upon it to pass through the aperture plate 25 and fall upon the revolving disk 26 driven by the motor 27 operating in synchronism with the motor 20, Fig. 1, the disks 18 and 26 being preferably similar or identical, or so that the period of passage of the beam of light through the angle subtended by the screen be substantially the same both in receiver and transmitter, to the end that corresponding spots register at correspondingly relative locations on both instruments, or follow each other at determinable intervals due to the inertia of the system. Although an electromagnetic circuit transmitting impulses to a reflecting diaphragm is here shown, it should be understood to lie within the scope of the invention to employ any other known means of varying the brilliancy of a pencil or beam or of a light source itself by means of variations of intensity in, or frequency of, electrical impulses applied to a device whose light emanating, producing, radiat-

ing, transparency, reflecting or transmission properties are affected by variations of electrical character. Also, any known means of increasing, diminishing, amplifying or damping the impulses produced by or employed with the apparatus herein described may be used.

In Fig. 3, rays pass through the lens c, as shown by the arrowed lines, to fall upon the screen s⁴, those falling upon one-half 29 of the screen being received upon the disk 41, while those falling upon the other half 30 fall upon the disk 42, after passing through aperture plate 38 and the revolving shutter 39 (later described), the number of disks, slots in the shutter and portions into which the screen is divided being equal, it being understood that the number of parts here shown—two—is merely in order to signify that there may be more than a single screen and a single disk used when desirable, each screen (or proportional part of any one screen) being used in combination with an independent shutter, or a sector of a common shutter. Or, instead of using 90 a plurality of disks all revolving at equal speed, there may be used a single disk revolving at a proportionately reduced speed, of increased diameter, and provided with an inversely greater number of reflecting 95 elements, the idea being merely to insure equal periods of passage of the pencil of rays cooperating with any given element over the screen area which the said element controls. The disks 41, 42, the gear 46 and 100 motor 47 are all attached to the spindle 44 passing through the bearing 43, the gear 46 meshing with the gear 45 which is twice the diametral pitch of the gear 46. The gear 45 and revolving shutter 39 are secured 105 to the spindle 48 which runs in the bearing 40, so that the angular velocity ratios of the systems on the spindles 44 and 48 are inversely as the number of disks 41, 42; or, more correctly, as the number of sets of elements employed to embrace or cooperate 110 with a given part of the screen.

In Fig. 4, the base 69 supports a bearing 68 in which runs a spindle 65^a to which is attached a gear wheel 65 provided with a 115 crank 66 having a handle 67 and meshing with a gear 61 which runs in a bearing 62 and which is mounted on the same spindle with a worm drive 63 which meshes with a gear 64 which is fastened to and drives a 120 shaft 56 passing through a bearing 57 and to which is secured the stator 47 of a motor. This motor is either electric or of other type and should be run synchronously or close to synchronous speed both in the receiving 125 and transmitting apparatus, or properly geared to the light reflecting elements, as 26, Fig. 2, to cause similar spots to register simultaneously in both instruments. To the spindle 56 are also secured collecting rings 130

53, 54 suitably insulated from the spindle by insulation 56 and connected with the stator of the motor or, if desired, to the rotor, depending upon what type of motor is used. 5 Power for running the motor is supplied through leads 59, 60 connected to stationary brushes 86, so that the angular position of the stator may be varied at will by turning the gear 65. To the rotor 52 is attached a 10 spindle 44 which runs in a bearing 43 and to which are secured disks 41, 42 and a gear 46 meshing with a gear 45 which is secured to the same spindle as a revolving shutter 39 which runs in the bearing 40. The shutter 15 39 is provided with two concentric apertures 50, 51, each subtending an arc of a complete circle inversely proportional to the number of disks used, and each of suitable width and the two suitably spaced so that only one 20 disk is exposed at a time to the effect of light rays from the screen (see Fig. 3), each disk being exposed through substantially a full revolution and the two disks being exposed consecutively. An adjustable aperture plate 25 (see Fig. 9) 38 having a horizontal aperture of length sufficient to permit rays to enter and leave both slots 50, 51, is suitably positioned in front of the shutter 39. When more than two disks are used—say, five— 30 the ratio of gearing between shaft and shutter should be as one to five, the shutter should have five concentric apertures each subtending adjacent apertures of 72 degrees, and each aperture should line up with a separate disk, and the screen should be made up of five sections each section provided with 35 elements controlling the direction of the reflected rays so that they fall upon and cooperate with the disk or disks utilized for receiving or transmitting the points of the view received upon that particular part of 40 the screen as a whole.

In Fig. 5, the center of curvature of the convex reflecting specular elements 82 on the screen 81 is behind the screen (one shown at the point 70), the angle subtended by the area of the element presented to the beam of light 83, and the angle of the general surface of the element as a whole being such 45 that the rays reflected as shown by the arrowed lines 76, 77 will be received upon and reflected by the element upon which they fall in the general direction shown by the line 79 which forms the same angle with the normal 78 to the element at the point of intersection of the axis 75 as does the said axis 50 75. If the lines 76, 77 are produced to pass through the screen they intersect at a point 55 72 in the plane 71, back of the plane of the screen, so that the angle 74 formed between them is substantially twice the angle 73 formed between the normals to the outside edges of the element; in other words, twice the angle of curvature of the element. This 60 type of multi-power reflecting screen, to- 65

gether with an analysis of its design to suit various conditions of light projection and reflection to embrace viewing angles of predetermined magnitude is described in applicant's patents aforesaid. A flat screen or a plurality of screens such as 81 provided with convex spherical elements of the proper curvature and angle and at the proper angle to the incident pencils or cones of light from a lens as *c*, Fig. 3, and conforming with the design indicated in Fig. 5, will be adapted for use in the several instances here shown on account of securing a concentrated directional beam or limited divergence. Since the area of the elements presented to the light affects the sharpness of definition, their size should be determined by the degree of desirable delineation, which in turn is governed by the rapidity with which successive impulses may be transmitted, it being understood that the higher the rate of transmission obtainable the greater the sharpness and size of the picture, so that when moving pictures are to be transmitted the speed of successive impulses should be from 100,000 per second, upward, for a single circuit system. 70

In Figs. 6 and 8, plane or slightly concave similar or identical reflectors 98 are spaced to subtend equal angles around the spindle 44 and are adjustable by means of screws 97 threaded into flanges 96, 99 of the member 95, the whole arrangement taking the place of one or more disks 41, 42, Figs. 3 and 4, and there being preferably the same number of reflectors 98 as there are strips 1 to 8, Fig. 1, each reflector being at such an angle as to control the light to or from one of the said strips. After the angles of the reflectors are adjusted by means of the screws the reflectors may be cemented in place and the screws removed. It should be understood that the angle subtended by each reflector with respect to the axis about which the group of reflectors revolves is substantially half the angle subtended by the vertical height of the screen as in Fig. 1, with respect to the said axis, so that each successive reflector is presented to successive strips of the screen in rapid succession and with a minimum time loss between them. 75 It will be seen that each reflector 98 is perpendicular to a plane passing through the axis 44, but all are of varying and constantly increasing degrees of obliquity with respect to a plane at right angles to the said axis, the angle of variation of obliquity of the general surface of successive reflectors being substantially half the angle subtended by the strips, as 1, 2, etc., Fig. 1, with respect to the middle point on the reflector, as 17, Fig. 1. The dimensions of the active (working part, as determined by the shutter and aperture plates, Figs. 3 and 4) may be readily determined by experiment with sources of different dimensions and divergence, or

by the use of additional lenses or aperture plates to secure a parallelling of the rays or the elimination of undesirable stray rays. Also, the sizes, design, spacing, dimensions, speed, proportions and arrangement of the various factors or parts going to make up the complete outfit shown in this specification may be determined by experiment or in accordance with optical, mathematical, mechanical, electrical, physical or other scientific or basic principles governing the design, use, operation and maintenance of apparatus of the character herein described.

In Fig. 7, the general surface of the disk 49 is cylindrical, or more like a spiral, since the mean point of each differently oblique reflecting face 85 lies on a circle. The general surface of each element 85 is equally oblique to adjacent elements in a plane taken through the middle of the disk 49 at right angles to the spindle 84, and the angle between the elements and the said plane varies in accordance with the description given for Figs. 6 and 8. A slight modification of this type of disk is shown in my copending application, S. N. 162,311. This type of disk is to be used in place of other types of disks, if desired, the advantage of tipping the elements like ratchet teeth is to enable the placing of the cell 13, Fig. 1, or the receiving device, Fig. 2, below or above the horizontal plane through the middle of the screen. Instead of arranging the elements like saw teeth, it is evident that they may be grouped or assembled with contacting edges, or substantially so, as shown in Fig. 6, but ground and polished and integral with the disk itself. This disk should be made of, or plated with, silver or some highly reflecting metal, and all elements should subtend substantially equal arcs or angles of the circumference of the disk, although this is not necessary, since the prime requirement is that when both the transmitter and receiver employ reflecting disks of the type here shown, the angular velocity of the elements or their periods of operation at both the receiving and sending stations be identical. Any desired number of disks may be used, either side by side or on different shafts, and any desired number of elements may be cut on the disks, a good number being forty to fifty per disk.

In Fig. 9, the thin metal plate 38 has an aperture 103 whose opening may be varied by sliding the shutters 102 under the screw heads 104.

In Fig. 10, the lines 24, 28 and the screen s^2 correspond to those shown in Fig. 2. A projection lens d placed in front of the screen s^2 will produce upon a larger screen (not shown) images appearing upon the screen s^2 .

In Fig. 11, the curved screen 112 having reflectors 113 is one of the types shown in

applicant's patents aforesaid, and is adapted for use in the device in combination with objective lenses having a curved focal surface instead of a true focal plane.

In Figs. 12 and 13, faces 107 are ground and polished on the periphery of the glass ring 106. Light rays 109 enter the flat surface 108, pass to the reflecting surface 111, are reflected to the outside of the ring and refracted at different predetermined angles 75 by the faces 107 as the ring is revolved upon its axis.

In Fig. 14, the disk 18 receives and reflects rays as shown by the arrowed lines to fall upon a disk 18^a which revolves in synchronism with the disk 18 and on an axis at right angles thereto. As these disks revolve the light pencil moves rapidly over the bank of sensitive cells 114 each of which is momentarily connected in the transmitting circuit by means of a contacting device operating in synchronism with the passage of the light beam over the cells, the wires 115 leading to the contactor (not shown).

In Fig. 15, the metal shutter 39^a is for use with a system having four disks, each aperture 116, 117, etc., subtending an angle of ninety degrees, and arranged so that as the shutter revolves successive disks are exposed so as to operate in cycles.

In Fig. 16, the disks are assumed to revolve clockwise and to be rigidly mounted side by side on the same spindle, as in Fig. 3 (and not edge to edge, as here shown, for diagrammatic purposes). The angles of the several reflecting faces are such that 87, 91 and 95 are the elements controlling the direction of light to the vertical strips each the farthest to the right of each section of a three-part screen, the other elements on each disk being as described for Figs. 3, 6, etc.

In Figs. 17 and 18, a lens 122 in the transmitter receives light from the view (not shown) and directs these rays to a screen having three parts d , e , f , one-third of the total screen area being exposed at any given instant by means of the continuous belt shutter 128 running on rollers 132 supported by bearings 133 and having three equally spaced apertures. Consider a single section d : this section is three elements wide by nine high (see Fig. 18) and each element, as 120^a reflects light to a corresponding single cell, as 120, in a bank of light-sensitive cells each of which is electrically connected as shown in Figs. 1, 14, or otherwise, as is well known in the art.

I claim:

1. In apparatus of the class described, in combination, a plurality of coaxially disposed disks rotatable about a given axis, means for rotating said disks, each of said disks being provided with a plurality of mirrors, the said mirrors on one disk con-

trolling the direction of a beam of light derived from a suitable source to illuminate successively parts comprising a given area, and the mirrors on adjacent disks controlling the light to illuminate areas adjacent the aforesaid areas, and means for successively and cyclically exposing each of said disks during a predetermined portion of a complete revolution of each of said disks to the aforesaid beam of light.

2. In apparatus of the class described, means rotatable on a fixed axis, said means including a plurality of substantially juxtaposed light-deflecting elements disposed to embrace an arc of more than 360 degrees relative to the aforesaid axis.

3. In apparatus of the class described, means rotatable on a fixed axis, said means including a plurality of light-deflecting elements, the sum of the angles subtended between the centerlines of all of said elements, in succession, being more than 360 degrees relative to the aforesaid axis.

4. In apparatus of the class described, a plurality of light-deflecting elements disposed upon a surface of revolution and means for successively illuminating each of said elements by light rays derived from a suitable source, the length of arc embraced by all of said elements, in succession, being more than 360 degrees.

5. In apparatus of the class described, in combination, a plurality of light-deflectors disposed in a group rotatable on a fixed axis, said group as a whole comprising more than 360 degrees, means for rotating said group on said axis, a source of light, and means for directing rays from said source successively upon each of the said light-deflectors.

6. In apparatus of the class described, in combination, a plurality of light-deflecting elements disposed on a rotatable member and each controlling the direction of light rays to one of a plurality of different areas

on a given surface, the sum of the angles between the centerlines of all the said elements, in succession and relative to the axis of rotation of the aforesaid member, being more than 360 degrees, and means for exposing said elements each successively to control rays from said rotatable member to the given surface aforesaid.

7. In apparatus of the class described, in combination, a rotatable group comprising a plurality of light-deflecting elements disposed at substantially equal angles relative to the axis of said group and collectively embracing more than 360 degrees of arc relative to said axis, and means for successively and cyclically exposing each of said elements to light rays from a suitable source, and means for substantially simultaneously rendering the remainder of said elements optically inoperative.

8. In apparatus of the class described, in combination, a plurality of light-deflectors disposed in a group mounted on a shaft rotatable about a fixed axis, said group as a whole comprising more than 360 degrees, an electric motor mechanically connected to said shaft, a source of light, means for successively exposing each of said light-deflectors to rays from said source, said motor comprising a stator and a rotor, said rotor being mounted on said shaft, suitable bearings on said stator, said shaft being rotatable in said bearings, suitable bearings for supporting said stator coaxial with said rotor, means including suitable gearing for rotating said stator coaxially with said rotor, suitable electrical connections to said stator and to said rotor, said means for exposing said light-deflectors being controlled by the rotation of said rotor.

In testimony whereof, I, PAUL L. CLARK, have signed my name to this specification this 19th day of March, 1923.

PAUL L. CLARK.
